UNITED STATES PATENT OFFICE.

ARTHUR ROBERT THOMAS WOODS, OF LONDON, ENGLAND.

APPARATUS FOR LAUNCHING, LOWERING, AND RAISING BOATS.

Application filed March 4, 1927, Serial No. 172,793, and in Great Britain March 6, 1926.

This invention relates to apparatus for launching, lowering and raising ships' boats of that type in which the pulleys over which the fore-and-aft falls pass to the boat are carried at the outer ends of beams arranged athwart ships and adapted to be simultaneously moved outwardly from their inboard position corresponding with the stowed position of the boat to their out-board position 10 corresponding with the launching position of the boat, the beams being carried from suitable guides fixed to the under side of the deck immediately above the deck on which the boats are stowed, the ropes of 15 the said fore-and-aft falls being led over guide pulleys to respective barrels of a power-operated winch, the arrangement being such that the boat is first, by the operation of the winch, raised from its chocks, 20 and then by simultaneously moving the beams carried clear of the ship's side so that it may be lowered on to the water, the simultaneous movement of the beams in one known mode of construction being effected 25 by the operation through worm gear of a shaft arranged at right angles to the beams and carrying spur pinions gearing respectively with racks attached to the said beams; and the present invention has for its object 30 the improvement of this type of gear and the provision for use in combination with it of means whereby, when the ship is docking, the boats, which in their normal inboard position overhang the ship's side, may be 35 stowed further inboard.

According to the invention the beams are moved simultaneously inwardly and outwardly by means of worms gearing directly with racks formed on or attached to the 40 beams, the respective beams being preferably inclined to the respective axes of the shafts carrying the operating worms, so that the rack teeth may be cut with their sides normal to the length of the beams; the beams 45 being preferably inclined to a normal transverse plane of the ship, whereby the said worm shafts are normal to the fore-and-aft centre plane of the ship and are therefore adapted to be coupled together by ordinary 50 gearing adapted to effect simultaneous operation.

The beams are preferably built of channel sections united by side plates, one of the channels of each of the beams having formed 55 on the central portion of its breadth a rack adapted to engage with its respective oper-

ating worm; the guide brackets by which the beams are carried being provided with rollers engaging respectively with the upper and lower surfaces of the beams, and the two 60 transverse shafts which carry the respective worms being arranged to be operated simultaneously by gearing which connects the shafts together and which connects both shafts to one of two or more hand-operated 65 launching gears.

The means by which the boats, when the ship is docking, can be moved from the position in which they are normally stowed, to an extreme inboard position in which they 70 lie within the plane of the side of the ship, comprises a pair of beams fixed to the under side of the deck above the boat deck, each provided with a trolley shackle carried by rollers adapted to run along the inturned 75 edges of the beam, the arrangement being such that the boat when in its normal stowed position is first raised clear of its chocks or skids by operation of the fore-and-aft falls, after which the boat in its raised position is slung from the trolley shackle, the two trolleys being then run along their beams and carrying the boat to its extreme inboard position.

The invention also includes details of 85 construction as hereinafter described and claimed.

I have illustrated my invention in the accompanying drawings, in which:—

Fig. 1 is a part elevation showing four 90 adjacent boats housed on the lower deck with the ship's structure arranged so as to permit the launching and stowage of the boats.

Fig. 2 is an elevation to a larger scale, 95
Fig. 3 a plan.

Fig. 4 a side elevation in section, and

Fig. 5 a view similar to Fig. 4 showing the beams and gear for hauling the boat into its extreme inboard position when the ship 100 is docking.

Fig. 6 is a plan view showing the boat in its inboard position shown in full lines
Fig. 5.

Figs. 7 to 9 illustrate details of construction.

Fig. 7 being a transverse section through one of the beams,

Fig. 8 a transverse section of the trolley shackle and beam, and

Fig. 9 a part plan of the gears for operating the worms.

The beams D^2 and D^3 are slidably carried in brackets d^{10} and d^{11} . The bracket d^{10} is directly carried from the deck A^2 , the bracket d^{11} is carried from a main bracket 5 K also secured to the deck A^2 . The bracket d^{10} is fitted with bearing rollers d^{12} , d^{12a} , and the bracket K is fitted with a bearing roller d^{13} . Each of the beams is built up, see Fig. 7, of channel sections d^{14} and d^{15} united by 10 side plates d^{16} . The member d^{14} has formed on the central portion of its breadth a rack d^{17} . The respective racks of the beams engage with respective worms M and M' each worm being keyed to one end of a shaft m^2 , 15 one end of which is journalled in the bracket m^1 , the other end being journalled in the bracket m^3 , and carrying a spur wheel m^4 gearing with a pinion m^5 keyed to a spindle m^6 one end of which is carried in the bracket 20 m^3 and the other end of which is carried in a bracket m^7 secured to the deck-house bulk-head a^3 . The spindle m^6 has keyed to it a chain wheel m^8 which is geared by a chain m^9 to a chain wheel m^{10} mounted on a 25 spindle m^{11} one end of which is journalled in a bracket m^{12} and the other end being journalled in a bracket m^{13} carried from the deck-house bulk-head. The shaft m^{11} has a squared end to take the operating handle m^{14} . 30 The shaft m^{17} is connected in similar manner to the shaft m^{11} the intervening members being similarly lettered to the corresponding members described but distinguished by an accent mark. 35 The forward chain wheel m^{10} has formed on its outer surface bevel teeth m^{15} gearing with a bevel pinion m^{16} keyed on a shaft m^{17} carried in brackets m^{18} ; the aft end of the shaft m^{17} carries a bevel pinion m^{19} gearing 40 with a bevel wheel m^{20} formed on the inside of the chain wheel m^{10} . The two worms M and M' may therefore be operated by either the forward handle m^{14} or aft handle $m^{14'}$. The axes of the worms M and 45 M' and their shafts m^2 and $m^{2'}$ are arranged athwart ships, but each of the beams D^2 and D^3 is inclined to the axis of the worm wheel and its shaft at an angle corresponding with the angle of the threads of the worm. 50 The forward boat fall E^2 passes from the boat winch F' round the fair lead roller e^{10} (see Figs. 2 and 3) round the pulley e^{11} thence round the fixed pulley e^{12} carried from the bracket d^{11} , then under the guide 55 pulley d^{18} (see Fig. 4) carried by the beam D^2 , and over the pulley d^{18} carried on the outer end of the beam D^2 and thence to the boat releasing gear e^{10} of the boat C'. The aft fall E^3 passes from the boat winch under 60 the fair lead rollers e^{13} (see Figs. 2 and 3) thence over the fair lead roller e^{14} round the fixed pulley e^{15} and thence to a pulley $e^{12'}$ carried on the bracket $d^{11'}$ of the aft beam, thence (see Fig. 6) under and over the pul-

ley $d^{17'}$ and $d^{18'}$ carried by the aft beam and 65 so to the aft attachment to the boat C'.

The boat winch F' may be of any suitable or usual type adapted to be operated either by power or by hand, and the barrel is usually divided into two sections one for the 70 forward fall and the other for the aft fall.

In launching a boat, the boat-winch is operated so as to lift the boat clear of the skids G' (see Figs. 2 and 5) upon which the boat is usually mounted in the position shown in full lines in Fig. 4. The worms M and M' of the two boat beams are then operated by one or both of the handles m^{14} and $m^{14'}$ through the gear described, rotation of the worms by engagement with the 80 racks moving the launching beams of the boat in an out-board direction, the boat winch being operated so as to pay out the falls as the length of fall between the roller d^{18} of the fixed roller e^{12} increases. When 85 the outer ends of the beams of the boat reach the position shown in dotted lines in Fig. 8 the boat is ready for lowering.

When the boat has to be taken in and housed aboard the operations described are 90 carried out in reverse order.

It will be seen that the outward half of the boat in the stowed position shown in full lines in Figs. 3, 4 and 6 extends outwardly beyond the sides of the ship. Should this projection interfere with the docking or other movements of the ship, provision is made for stowing the boats further inboard, as shown in Fig. 5. A beam P is fixed to the under side of the deck A^2 consisting (see Fig. 8) of two side members p^1 having in-turned edges p^2 , secured to the deck beam a^{10} by bolts p^3 and distance pieces p^4 . A U-shaped trolley shackle Q is provided having at each end an eye q^3 , a shaft q^2 carrying a pair of rollers q^1 , the respective rollers of the pair running in the concave guides formed by the turned-over ends p^2 . 100 105

The details of constructions in other respects may be modified in accordance with 110 the type of switch to which the gear is applied.

Having now fully described my invention, I declare that what I claim, and desire to secure by Letters Patent is:—

1. In apparatus of the type referred to for launching, lowering and raising ships boats, in combination; launching beams for the boats; a rack on each launching beam; a worm engaging with each rack; athwartship shafts carrying said worms; operating gear connected to the athwartship shafts to move the launching beams in an inboard or outboard direction; substantially as described. 115 120 125

2. In apparatus constructed in accordance with claim 1, mounting the launching beams on the underside of an upper deck, and pro-

viding the ship's side with openings through which the boats can be launched; substantially as described.

3. In apparatus as claimed in claim 1, 5 in combination; a pair of launching beams the outer ends of which are provided with pulleys to take the respective falls passing to the boat winch, the respective beams being slidably carried from the deck by 10 brackets fitted with rollers, the upper faces of the launching beams carrying racks and a pair of worms respectively engaging with said racks and carried on athwart ship worm shafts; the inner ends of said shafts 15 being connected together and to operating means to impart simultaneous longitudinal movement to the two launching beams; substantially as described.

4. In apparatus as claimed in claim 1, a 20 chain wheel to actuate each worm shaft, a

handle shaft provided with a chain wheel to operate the respective chain wheels on the worm shafts for imparting simultaneous longitudinal movement to the two launching beams; substantially as described.

5. In apparatus as claimed in claim 1, arranging the launching beams at an angle inclined to the athwart-ship worm shafts and arranging the teeth of the rack at right angles to the launching beam; substantially 25 30 as described.

6. In combination with apparatus as claimed in claim 1; a pair of athwart-ship beams; a trolley shackle on each beam from which shackles the boat is adapted to be 35 suspended; substantially as described.

In witness whereof I have hereunto set my hand.

ARTHUR ROBERT THOMAS WOODS.
